UNITED STATES PATENT OFFICE.

GEO. F. LUFBERY, OF NEW YORK, N. Y.

MACHINE FOR MAKING PAPER BAGS.

Specification of Letters Patent No. 28,188, dated May 8, 1860.

To all whom it may concern:

Be it known that I, G. F. LUFBERY, of the city, county, and State of New York, have invented certain new and useful Improvements in Machinery for Making Bags of Paper; and I do hereby declare that the following is a full, clear, and exact description of the same, reference being had to the accompanying drawings, forming part of this specification, in which—

Figure 1, is a longitudinal vertical section of a machine constructed according to my invention. Fig. 2, is a rear elevation of the same. Fig. 3, is a plan of the same. Fig. 4, exhibits the form in which the blanks of paper or other material of which the bags are to be made are cut before their introduction to the machine. Fig. 5, is a side view of one of the grippers, and its appendages, 20 on a larger scale than the other figures.

Similar letters and numbers of reference indicate corresponding parts in the several figures.

My invention consists in certain novel contrivances which take a cut and partly folded blank from a pile print it and paste the parts which are to form the lap and conveying it toward the apparatus by which the lap is folded; also, in a certain novel arrangement of the lap folding apparatus, and the lap pasting apparatus, the lap folding apparatus, and the contrivance for conveying the partly folded and pasted blank, to the lap folding apparatus, also in the arrangement of a fixed needle in such relation to the apparatus by which the finished bag is thrown out of the folding apparatus, that the bags will be strung together by the act of throwing them out of said apparatus.

40 To enable others to make and use my invention I will proceed to describe its construction and operation.

A, is the main shaft of the machine arranged horizontally in bearings in standards 45 B, B, erected upon a bed-plate or table C, which constitutes the base of the machine. This shaft carries a cylinder D, which serves the purpose of assisting to carry the partly folded blanks to the apparatus for folding 50 the side laps, of pasting the side laps, and of printing the card of the merchant or trader, or any other superscription on the outside of the bag. The said shaft also carries a number of wipers for giving motion, 55 the other parts of the machine and is fur-

nished with a driving pulley E, to receive the belt from which it derives its own rotary motion.

a, a, are two grippers attached to the cylinder D, for the purpose of taking from a stationary inclined feed board F, substantially like that of a printing press, the partly folded blanks, which before having been deposited on the said feed board have been cut and folded as illustrated by Fig. 4 60 that is to say they have been cut to the form represented by the lines b b, c c, d, e, f f, and then folded by hand, or other means, in the dotted line g, which is even with the edges f f, and at the middle of the length of 65 the bag, to bring the part d, c, c, on the part b, b, e. The width between c c, is equal to or slightly less than the intended width of 70 the bag, the fold g, forms the bottom of the bag, and the parts h, h, between the edges b 75 and c, constitute the side laps which have to be pasted and folded by the machine. The pieces thus folded are laid on the feed board F, with the parts c c d underneath, and the fold g, toward the cylinder. The 80 two grippers a, a, are arranged in line with each other, at a distance apart, less than the two edges c, c, of the blanks each being arranged to turn on one of two pins i, which are attached to the cylinder, each within a 85 recess j l, in one of two raised bands D', D', which are formed around the cylinder, the axes of the said pins being parallel with the axis of the cylinder; and each of the said grippers has a spring k, coiled around its 90 respective pin, and applied to it in such a manner as to tend to throw its point outward from the cylinder. Above the cylinder opposite the bands D', D', there are attached to a fixed bar G, two stationary arched plates 95 H, H, which are concentric to the cylinder, and very near to the peripheral surfaces of the said bands, the front end of said plates being so arranged that the grippers will strike them just after passing the lower 100 edge of the feed board, in their revolution with the cylinder, and so be caused to have their points thrown down over the edges l, l, of the recesses j l j l, and held there till the grippers pass from under the said plates. 105 Every time the grippers pass around the edge of the feed board, the attendant who stands in front of the machine pushes the top blank of the pile in under them, and as they pass under the plates they seize it, be- 110

tween their points and the bands D', D', and carry it around with the cylinder in the direction indicated by the arrow shown on the latter in Fig. 1. The external circumference 5 of the bands D', D', should be equal to about twice the length of the bag.

Nearer to the ends of the cylinder than the bands D', D', there are formed upon the cylinder two raised fillets D², D², extending 10 about half way around the cylinder, or as far around as the length of the longest bag to be made in the machine, the faces of the said fillets being concentric with the axis of the cylinder, and formed even with the faces of 15 the bands D', D', the said fillets being at a distance apart equal to the distance between the two edges c, c, of the blank, and commencing in line with the edges j, j, of the recesses j l, j l, of the said bands and extending 20 from thence around the cylinder in the opposite direction to that in which the cylinder rotates as indicated by the arrow shown on it in Fig. 1. These plates are for applying paste to the laps h, h, of the blank, 25 the paste being taken from two rollers I, I, which are arranged to rotate in a stationary paste box J, below the feed board, and which are caused to keep up the supply of paste to the faces of the said fillets by the 30 rotary motion imparted to them by the fillets revolving in contact with them. The laps h, h, are pressed against the pasted fillets by passing under two pressure rollers K, K, on a shaft L, that is arranged to rotate in bearings 35 above the cylinder.

At the middle of the length of the cylinder D, between the bands D', D', there is formed around it a broad concentrically raised band D³, the face of which is even 40 with the faces of the bands D', D', and in this band between the fillets D², D², there is arranged the form of type m, for printing the bag, the impression being produced by the blank passing with the form under a 45 roller M, on the shaft L, and the form being inked by an inking roller n, which is held by a frame N, arranged to vibrate upon fixed centers o, above the paste box and below the feed board, the said roller being 50 supplied with ink from a larger roller O, whose journals work in stationary bearings. The roller n, is held out of contact with the cylinder and in contact with the roller O, except while the form is passing it by means 55 of two friction rollers p, p attached to the frame N, resting against the cylinder itself, but just as the form is arriving opposite the said rollers n, the rollers p, p, drop into recesses q, q, shown dotted in Fig. 1, provided 60 in the cylinder to receive them, and the inking roller n, is forced into contact with the form by means of a spring r, which presses continually upon the frame N. The roller O, derives an intermittent rotary motion 65 through a band s, from a pulley on the

shaft I', of the paste rollers and so keeps up the supply of ink to the roller n, which is caused to rotate by contact with it.

Behind the roller there is arranged a swinging fly Q, of the width of the bag and 70 of somewhat greater depth, the journals of the said fly being fitted to stationary bearings b, b, projecting but a short distance above the surface of the bed plate or table C, and one of the said journals being furnished 75 with a crank u, see Fig. 1, which is connected by a link u' with the lower arm of a lever P, which works on a fixed fulcrum shaft v, which extends from one standard B, to the other. This lever P, has also connected with 80 its lower arm a spring w, which tends to draw it forward, and so by its action on the link u', and crank u, to hold up the fly Q, against the back of the cylinder. The part of the fly which comes against the cylinder 85 is made with prongs x, x, which enter the spaces between the bands and fillets of the cylinder D, in such a manner that the blank may pass over them as it is carried around with the cylinder. The blank is liberated 90 from the grippers before it arrives at the prongs of the fly Q, by the escape of the grippers from under the plates H, H, but continues to adhere to the pasted fillets D², D², of the cylinder till its arrival over the 95 prongs x, x, of the fly, after which the continued revolution of the cylinder causes it to be stripped off the said fillets by the prongs x, x, and to pass straight down the back of the fly, which continues stationary 100 in contact with the cylinder till the blank is very nearly stripped therefrom, when by the action on the upper end of the lever P, of a wiper z, carried by one of two wheels R, R', 105 that are fast on the main shaft A, the said lever is caused through the agency of the link u', and crank u, to throw it (the fly) down suddenly upon the horizontal folding bed S, which is elevated a little above the bed plate or table C, and so to deposit the 110 blank upon the said bed. The action of the wiper z, upon the lever P, is only momentary and as soon as the pasted and printed blank is deposited upon the folding bed, the 115 said wiper escapes from the said lever and allows the spring w, by its action on the said lever to throw the fly upward again into contact with the cylinder.

The width of the folding bed S, is exactly 120 equal to the intended width of the finished bag, consequently as much narrower than the wider portion of the blank, as the width of the laps h, h. The said bed has hinged to its sides the two lap folders T, T, consisting of two straight flaps of wood or metal, which 125 when the blank is deposited on the bed by the fly Q, are stationary in a nearly upright position, only inclining slightly from each other as shown in Fig. 2, in which condition they are held by the springs 6, 6, against the 130

blocks 7, 7, standing up from the table C, above the folding bed. The blank in being carried downward by the fly between these folders has the laps *h*, *h*, turned up as shown 5 in Fig. 2, where it is represented in blue color, and immediately after the fly Q, has been raised again the said folders are thrown over toward each other, and so made to fold over the laps *h*, *h*, and press their pasted 10 sides down on the part *d*, *c*, *c*, of the blank thus completing the bag. This operation of the folders is produced by the action against their outer sides of two horizontal cams U, U, somewhat resembling bell-cranks which 15 are arranged to turn upon stationary pins 8, 8, secured in the blocks 7, 7, the said cams being brought into action on the folder by means of two wipers 10, 10, carried by the wheels R, R', on the main shaft, upon the 20 upper end of two levers V, V, which are arranged to work on the fulcrum shaft *v*, and which have their lower ends connected by rods 11, 11, with the said cams. When the wipers 10, 10, have passed the levers V, V, 25 which they do very quickly, the lower ends of the said levers are drawn forward again to move the cams out of the way of the folders by means of springs 12, 12, connecting them with the table C, and the folders 30 are raised again by the springs 6, 6, to the position represented in Fig. 2.

During the above described operation, there lies flat upon the folding bed S, below the bag a fly W, substantially like Q, attached to a rockshaft 13, whose journals are fitted to fixed bearings 18, 18, arranged in rear of the folding bed. This fly W, is held down upon the bed, during such operation by a spring X, one end of which is connected with one of the standards B, and the other with a cord 14, which is wound partly around and secured to a roller 15, on the rockshaft 13, but after the folding has been performed and the folders T, T, have returned 40 to the position shown in Fig. 3, is turned completely over in the opposite direction, from the axis of its rockshaft, to throw the bag off the folding bed by the action of a wiper 16, attached to the wheel R', on the 45 upper end of a lever Y, which is arranged to work upon the fulcrum shaft *v*, and whose lower end is connected, by a cord 19, running around a guide pulley 17, with the roller 15, said cord passing around or partly 50 around the said roller. Near the rockshaft 13, there is a hole 20, in the fly W, to receive a stationary needle 21, which has an eye near its point and is so arranged in the

form of an arc concentric to the axis of the rockshaft 13, that it will pass through the 60 said hole when the fly is swung back to throw the bag from the folding bed. In passing through the said hole the said needle also passes through the bag near the mouth thereof, and by keeping the needle threaded 65 with twine, the bags are in this way strung together, in the manner generally required by merchants and traders.

The above described operations are all 70 performed once, and one bag produced during every revolution of the main shaft A, and as soon as one hundred or any other number that it may be desired to string together for sale, have been produced, a bell 75 22, is rung by the action of a wiper 23, attached to a ratchet wheel 24, of the desired number of teeth which is moved one tooth for every revolution of the main shaft by means of a pawl 25, operated by an eccentric 80 wrist carried by the said shaft.

What I claim as my invention and desire to secure by Letters Patent is:

1. The cylinder D, constructed with bands and fillets D', D², D³, and furnished with grippers substantially as herein described to 85 perform the several operations of taking the blank from a pile and conveying it toward the lap folding apparatus, and of pasting the laps and printing it while on its way to such apparatus.

2. The grippers *i*, *i*, applied and operated by stationary arched plates H, H, in combination with springs *k*, *k*, substantially as herein described.

3. The pronged fly Q, applied and operating in combination with the cylinder D, to strip the pasted blank from the paste fillets of said cylinder substantially as herein described.

4. The arrangement of the folding table 100 S, and lap folders T, T, the fly Q, and the pasting and printing cylinder D, substantially as herein described.

5. The fly W, applied in combination with the folding bed S, in the manner and for 105 the purpose herein specified.

6. The stationary curved needle applied and operating in combination with a hole in the fly W, or its equivalent by which the bags are thrown out of the folding apparatus substantially as and for the purpose specified.

GEORGE F. LUFBERY.
